[57] CLAIM

The ornamental design for a luggage tag, as shown and described.

DESCRIPTION

FIG. 1 is a front elevational view of the luggage name tag and plastic rivet showing my new design;
FIG. 2 is a rear elevational view thereof;
FIG. 3 is a left side elevational view thereof;
FIG. 4 is a right side elevational view thereof;
FIG. 5 is a top plan view thereof;
FIG. 6 is a bottom plan view thereof;
FIG. 7 is a perspective view thereof; and,
FIG. 8 is a reduced perspective view thereof, with the
broken line showing for illustrative purposes only and
forming no part of the claimed design.
